READING GLASS WITH ADJUSTABLE
LINE GUIDE

Elsie H. Salter, Los Angeles, Calif.

Application October 13, 1947, Serial No. 779,452

5 Claims. (Cl. 88—39)

1

My invention relates to office equipment and more particularly to reading glasses especially adapted to be used in offices for the purpose of facilitating the copying of names from telephone books, trade guides and the like.

The object of my invention is to provide a reading glass of the character indicated, mounted in a rectangular frame equipped with legs and adapted to be placed on an opened book of the class indicated.

Another object of my invention is to provide a reading glass of the character indicated above, the frame of which extends over one printed column of the page, on which the reading glass stands.

A further object of my invention is to provide a reading glass of the character indicated above the frame of which is equipped with a transverse guide adapted to be slidably moved longitudinally of the frame to indicate the printed line to be copied.

Other objects of my invention not specifically mentioned may appear in the following specification describing my invention with reference to the accompanying drawing illustrating a preferred embodiment of my invention.

It is, however, to be understood, that my invention is not to be limited or restricted to the exact construction and combination of parts described in the specification and shown in the drawing, but that such changes and modifications can be made, which fall within the scope of the claims appended hereto.

In the several figures of the drawing similar parts are designated by similar reference characters and

Figure 1 is a view in top plan of a reading glass constructed in accordance with the present invention;

Figure 2 is a sectional view taken substantially on the line 2—2 of Figure 1;

Figure 3 is a sectional view taken substantially on the line 3—3 of Figure 1;

Figure 4 is a fragmentary side elevational view illustrating in detail the mounting for the lever; and

Figure 5 is a detailed sectional view taken substantially on the line 5—5 of Figure 1.

The reading glass forming the subject matter of my invention comprises a magnifying lens 10 of conventional convex shape and having a rectangular outline.

The lens 10 is mounted in a rectangular frame α comprising two transverse end portions 11 of substantially angular cross section, the upper

flange of which extends substantially horizontal and the other flange of which is arranged substantially vertical.

In the inner surface of each vertical flange, a substantially horizontal groove 12 is provided just below the horizontal flange and is adapted to receive the corresponding transverse end of the lens 10.

The two transverse frame end portions 11 are connected with each other by two longitudinal side members 13 secured to or integrally formed with the two transverse end members 11.

Each side member 13 has an angular cross section and comprises a substantially horizontal flange 14 and a substantially vertical flange 15. In the latter, a longitudinal groove 16 is arranged in its inner surface just below the horizontal angle flange 14 at the same level as the groove 12 in the vertical flange of each transverse angle 11, so that the longitudinal edges of the lens 10 are adapted to be received in the longitudinal grooves 16.

Adjacent to the lower edge of the vertical flange 15 of each angular side frame member 13 a longitudinal slot 17 is provided and extends approximately over the entire length of the angular side member.

At each corner of the above described frame α , a leg 18 is adjustably secured to said frame α in any desired conventional manner, so that the height of each leg 18 may be regulated and the lens 10 may be arranged parallel to and at a preferred distance from any surface, on which the frame rests. The lower end of each leg is equipped with rubber tip 19 to prevent accidental sliding movement of the reading glass on the surface supporting said glass.

A substantially rectangular guide plate 20 is slidably supported between the vertical flanges 15 of the longitudinal side members 14 of the frame α . At one end of said guide plate an angular bracket 21 is formed integrally with said plate just below the top edge of the guide plate and extends through and is arranged slidably in the slot 17 in the vertical flange 15 of the longitudinal side frame member 13.

At the other end of the guide plate 20 an outwardly extending bracket 22 is formed having the shape of a rectangular triangle, the hypotenuse of which extends upwardly and outwardly from the end edge of the guide plate, so that the upper side of this triangle extends horizontally from said end edge and is located below the lower edge of the side frame member 13.

A guide member 23 comprises a top plate 23

extending horizontally through the longitudinal slot 17 in the side frame member 13, to the underside of which is fixed a bracket 22 which is joined to the adjacent end edge of the plate 20. On the inner end of the top plate 23 an end piece 24 is formed extending downwardly at a right angle to the top plate, and on the lower end of the end piece a bottom guide piece 25 is formed and extends outwardly at right angles to the end piece 24. On the outer end of the bottom guide piece a front guide 26 is formed and extends upwardly at a right angle to the bottom guide piece.

The inner end of the top plate 23 engages the lower edge of the slot 17 slidably and the bottom guide piece 25 engages the bottom edge of the vertical flange 15 in a like manner. The end piece 24 engages the inside surface of the vertical flange 15 slidably and the front guide is adapted to slide along the outside surface of said vertical flange.

When the guide member b is in the position described above, the top plate 23 extends outwardly from the frame a and on each side of the forward portion of said top plate, a short downwardly extending wing 26' is formed. A U-shaped yoke 27 is pivotally mounted on a shaft 28 extending through the wings 26' and the flanges of the yoke 27 adjacent to the ends of said parts. The U-shaped yoke is arranged so that it is substantially inverted on the top plate and the web of said yoke is located above the top plate.

A clamp lever c has a comparatively narrow intermediate portion 29, an outside finger lever portion 30 and an inside clamp portion 31. It is welded with its narrow intermediate portion onto the web of the yoke 27, so that the clamp portion 31 is located over the horizontal flange 14 of the side frame member 13.

A helical spring 32 surrounds the shaft 28 between the wings 26. One straight end of said spring engages the underside of plate 23 and the other end of the helical spring 32 engages the lower surface of the finger lever portion 30 urging the clamp portion 31 downwardly into engagement with the horizontal flange 14 of the side frame member 13.

The above described reading glass is used preferably for copying addresses from telephone books, trade guides and the like.

The reading glass is placed on a page of an opened telephone book or the like, so that it extends over one column 33 of names. The legs 18 are adjusted, so that the distance from the lens 10 to the printed matter in the column 33 produces the best result in easy reading.

The finger lever 30 is pressed downwardly against the pressure of the helical spring 32 pivoting the clamp lever c about the shaft 28, so that the clamp portion 31 is disengaged from the top surface of the horizontal flange 14 of the side frame member 13.

The guide plate 20 is then moved into position to indicate the printed line to be copied.

The spring 32 returns the clamp lever c into clamping position, when the finger lever 30 is released and secures the guide plate 20 against accidental displacement.

The rubber tips 19 prevent accidental movement of the reading glass on the page on which it rests.

Having described my invention I claim as new and desire to secure by Letters Patent:

1. A magnifying reading device comprising a substantially rectangular frame having two longitudinal side members, a lens mounted within the frame, and a transverse guide plate arranged ver-

tically between and supported on the side members to be slid along said members, said side members being provided with longitudinal slots lying in a plane passing beneath the lens, the guide plate having on one of its ends a bracket extending through the slot in the adjacent side member and slidably engaging the same, a triangular bracket extending from the other end of the guide plate below the adjacent side frame member, a guide member secured on top of the triangular bracket, extending through the slot in the second side member and slidably engaging the portion of said side member located under the slot therein.

2. A magnifying reading device comprising a substantially rectangular frame having two longitudinal side members, a lens mounted within the frame, and a transverse guide plate arranged vertically between and supported on the side members to be slid along said members, said side members being provided with longitudinal slots lying in a plane passing beneath the lens, the guide plate having on one of its ends, a bracket extending through the slot in the adjacent side member and slidably engaging the same, a triangular bracket extending from the other end of the guide plate below the adjacent side member, a guide member secured on top of the triangular bracket, extending through the slot in the second side member and slidably engaging the portion of said side member located under the slot therein, and a spring biased holding lever carried on the guide member for releasably engaging the adjacent side member for securing the guide plate against accidental movement relative to said frame.

3. A magnifying reading device comprising a substantially rectangular frame having two longitudinal side members, a lens mounted within the frame, and a transverse guide plate arranged vertically between and supported on the side members to be slid along said members, said side members being provided with longitudinal slots lying in a plane passing beneath the lens, the guide plate having on one of its ends a bracket extending through the slot in the adjacent side member and slidably engaging the same, a triangular bracket extending from the other end of the guide plate below the adjacent side frame member, a guide member secured on top of the triangular bracket, extending through the slot in the second side member and slidably engaging the portion of said side member located under the slot therein, a spring biased clamp lever pivotally supported on the guide member and having clamping frictional engagement with the top surface of the adjacent frame side member under the spring pressure, and a finger lever forming a part of the clamp lever for facilitating its disengagement from the frame side member.

4. A magnifying reading device comprising a substantially rectangular frame, supporting feet for positioning the frame horizontally above a supporting surface, a lens mounted within the frame, said frame having two spaced side members each of which is provided with a longitudinal slot, the plane of the slots passing beneath the lens, a relatively thin guide plate disposed vertically between the slotted side members of the frame, means connected with each vertical end edge of the guide plate adjacent to one longitudinal edge for sliding engagement in the slots whereby said plate is suspended beneath the lens to substantially span the vertical distance between the underside of the lens and the said underlying supporting surface, the said plate suspending

means being slidable in the slots for the movement of the plate horizontally beneath the lens, and means connected with the plate and projecting laterally beyond the outer side of one of the slotted side members for securing the plate in adjusted position.

5. A device of the character stated in claim 4, wherein the last named means comprises a laterally extended plate connected with the first mentioned plate and disposed below the plane of the top of the frame, a pivot pin carried upon and transversely of the outer end of the laterally extending plate, a lever oscillatably mounted on the pivot pin and having an end in frictional contact with the adjacent side member of the frame, and spring means forming a yielding connection between the said laterally projecting plate and said lever and constantly urging oscillation of the lever in a direction for maintaining the said frictional engagement with the side member of the frame. 20
